UNITED STATES PATENT OFFICE

JOHN B. SIDEBOOTHAM, JR., OF PHILADELPHIA, PENNSYLVANIA

METHOD OF MAKING TAPE FOR ELECTRICAL PURPOSES

Application filed February 8, 1928. Serial No. 252,740.

This invention, stated in its broadest terms, relates to a method of making tape and has more especial relation to the method of making tape for electrical purposes.

5 The object of the present invention may be said to reside in the provision of means whereby thread from a left hand twist yarn, of single ply, and thread from a right hand twist yarn, either single or multiple ply, are 10 fed to conditioning apparatus, and thereafter introduced to a loom for weaving of the threads, the resultant product being a tape which will lie relatively flat in use in contradistinction to becoming twisted or curled, 15 thus providing for the more efficient handling of the tape in the various uses to which it is to be put.

The invention consists of the method hereinafter described and finally claimed.

20 In order to describe fully the method embodying my invention, the accompanying sheet of drawings is provided, in which:

Figs. 1, 2, and 3 diagrammatically illustrate the manner of presenting, winding, and 25 treating the thread.

Fig. 4, represents diagrammatically the loom apparatus; and

Fig. 5, is a view of the finished tape.

According to the present invention, it is 30 desirable to provide a tape for electrical purposes in which the same as unwound from its spool lies relatively flat, so that the operator can more conveniently use the tape without the usual trouble of curling and twisting. This I accomplish by taking, for example, one or more left hand twisted yarns, of single ply, designated 1, in Fig. 1, the threads in which left hand twist yarn, of single ply, are passed through a guide 3, and

40 directed to reeds 4 and 6. Stop mechanism 5, is provided, as is usual in conventional mechanism of this character. Small rollers 7 and 8 are provided over which the combined threads travel and are introduced to and 45 wound upon a large roller 9. This operation is renewed as often as desirable, and in the present instance, for explanatory purposes, three large rollers 9 are provided with thread, some of which threads may have been wound 50 left handed and somerighthanded. Asam-

ter of fact, in the drawings as shown at the right hand side of Fig. 2, the first two large rollers 9 may have wound thereon right hand twisted yarn while the remaining roller may have wound thereon left hand twisted 55 yarn. The threads from the large rollers 9 are guided to and through a container 10 in which is provided a suitable bath or liquid, and before egressing from the container 10 the threads are guided over rollers and pass 60 through a wringer 11 for removing excess moisture from the threads. After leaving the wringer the threads pass through the drier 12, which is of conventional form, and guided to and wound upon large rollers 13, 65 the left hand twisted thread being maintained uppermost during a guiding period. These rollers 13 are then removed from the above described apparatus and placed upon the apparatus shown in Fig. 3, and the 70 threads are passed between tension rolls 14 to three small rolls 15, 16, and 17. The above described steps, described with respect to Figs. 1, 2, and 3 of the drawings, may be termed "beaming", "dressing", and "slashing" operations. These three rolls 15, 16, and 17 are then positioned with respect to 75 a loom structure 18, as shown in Fig. 4, which is of conventional form, and the left hand threads of single ply, and the right hand threads, either single or multiple ply, having been properly treated and dried are presented to the loom and regular weaving takes place, with the exception that the threads as introduced to the loom are twisted 80 left handed of single ply, and right handed of single ply, so that when the final product 19, as shown in Fig. 5, comes from the loom the fabric lies relatively flat in contra-distinction to being coiled or wrinkled, as in conventional tape as used for electrical purposes. This is particularly advantageous 85 when the tape is being unwound from a spool, as is readily apparent and has been already pointed out in the object so that repetition thereof is superfluous.

I am aware that the invention may be embodied in other specific forms without departing from the spirit or essential attributes thereof, and I therefore desire the present 100

embodiment to be considered in all respects as illustrative and not restrictive, reference being had to the appended claim rather than to the foregoing description to indicate the scope of the invention.

Having thus described my invention, what I claim as new and desire to secure by Letters Patent, is:

The herein described art of making tape 10 of narrow fabric loom weaves of more than one strip at a time for electrical purposes which consists in taking bobbins of right and left hand twisted thread of single ply, presenting first the thread to reeds and then 15 winding upon large separate rolls left hand twisted thread and winding upon other large rolls right hand twisted thread, presenting said thread to a suitable liquid dressing, which dressing has the tendency to strengthen 20 said single ply thread, squeezing excess liquid from said thread, then drying the thread and feeding the same to separate large rolls, during which feeding of thread the left hand twisted thread is maintained uppermost or above the right hand twisted 25 thread, then winding the thread separately upon small rolls, and thereafter interweaving said left hand and right hand twisted thread from the small rolls by a loom arranged to operatively receive the thread from 30 said small rolls, the resultant product being a tape for electrical purposes adapted to lie flat and uncurled.
